UNITED STATES PATENT OFFICE.

WILLIAM H. POTTER AND JOHN E. BENSON, OF CHICAGO, ILLINOIS, ASSIGNORS TO THE NYE TOOL AND MACHINE WORKS, OF CHICAGO, ILLINOIS, A CORPORATION OF ILLINOIS.

DIE-THREADING MACHINE.

1,137,020.

Specification of Letters Patent.

Patented Apr. 27, 1915.

Application filed April 6, 1914. Serial No. 829,776.

To all whom it may concern:

Be it known that we, WILLIAM H. POTTER and JOHN E. BENSON, residing at Chicago, in the county of Cook and State of Illinois, both citizens of the United States, have invented a certain new and useful Improvement in Die-Threading Machines, of which the following is a specification.

Our invention relates to die threading machines and the general object of the invention is to provide a machine by the aid of which threads may be formed very accurately upon the die; also to provide a machine in which a full range of adjustments is possible so that the machine may be adapted to cut dies of various sizes and to cut dies in which the blades or chasers are set either parallel to the axis or obliquely thereto in the manner referred to in the trade as "on the spiral."

Another object is to provide a construction which will result in great rigidity of the parts without making them unnecessarily heavy or large.

These general objects are obtained as a result of a number of specific characteristics which will be hereinafter more particularly described and claimed, and are illustrated in the accompanying drawings in which—

Figure 1 is a plan view of the assembled machine. Fig. 2 is a vertical section thereof on the line 2—2, Fig. 1. Fig. 3 is a top plan view of the lead block, die holder and associated parts. Fig. 4 is a bottom plan view of the hob carrier and parts for driving the hob and adjusting it to cut dies of different diameters. Fig. 5 is a detail in plan showing one portion of the die holder. Fig. 6 is a front elevation of the parts shown in Fig. 5. Fig. 7 is a plan view of the latch mechanism for locking the die holder while the thread is being cut upon any given chaser. Fig. 8 is a face view of a die showing the chasers acting upon a pipe, this view illustrating the desirability of "rake" or "clearance" upon the chasers. Figs. 9 and 10 are sectional elevations showing details of the latch and the means for adjusting the latch upon the lead block. The planes of section in the two views are at right angles to each other, the plane of section of Fig. 9 being indicated by the line 9—9 in Fig. 10.

Similar numerals refer to similar parts throughout the several views.

The bed plate or stationary part of the machine consists of a table 1 of any suitable outline. In the present instance this is supported upon a number of legs 2. This block has a central aperture having an internal screw thread 3 which cooperates with an external screw thread 4 formed upon the sides of the lead block 5. The threaded surfaces 3 and 4 form a lead screw for the lead block so that the latter will progress in an axial direction (vertical in the present instance) when rotated by means of the handle 6. Ours may be termed a "hand feed" machine, and the feeding of the work to the hob is accomplished by rotating the lead block by said handle 6.

In our machine, as here illustrated, the axis of the hob remains stationary so long as the machine is operating on dies of any given diameter; in other words, the axis of the hob is shifted only to adjust the hob to dies of various sizes, and we will first describe the hob carrier and means whereby the hob is driven and adjusted.

The hob 8 is located at the upper extremity of a spindle 9 journaled in the upper boss 10 rising from the plate 11, as best shown in Figs. 2 and 4. Said plate constitutes an adjusting segment and is pivotally attached to the under side of the table by a fulcrum stud 12. Said segment may be rotated about its pivot by handle 13. It has slots 14, preferably two in number, through which pass set screws 15. Said set screws may be tightened by nuts 16, one of which is operated by handle 17, as shown in Fig. 1. By adjusting the segment the hob may be adjusted closer to or farther from the central axis of the lead block to produce dies of different diameter. The hob is rotated by a gear 20 at its lower end meshing with a worm 21 rigidly secured to a drive shaft journaled in suitable bearings 23 mounted on the under side of the segment. This shaft is driven by a band wheel 24 or equivalent power device.

On opposite sides of the segment handle 13 are adjustable stops which consist of screws 25 mounted in lugs 26. These stops enable the operator to quickly bring the segment to a previously determined position.

The boss 10 in which the spindle 9 is journaled passes up through a central opening 5^a in the lead block 5 and through a central opening 30^a in the die holder block 30. Said die holder block is externally threaded and screws into the central opening of the lead block. The means for securing the die to the die holder block are shown in detail in Figs. 5 and 6. In the form illustrated the holder block is provided with two lugs 32 in which are mounted set screws 33. These screws are adapted to press against two adjacent sides of the die, said die consisting of the body 34 and the chasers 35. The die is shown separately in Fig. 8 and is shown in position in the die holder in Fig. 3. The set screws 33 force the die against two blocks 37 which are adjustably mounted in housings 38, these latter parts being shown separately in Figs. 5 and 6. Said housings are secured preferably by screws 39 assisted by dowels 40. The blocks are longitudinally slotted and are adjustably held by set screws 41 so that the blocks may be retained in the proper position to hold the die accurately centered.

There are usually four chasers to a die, and the die holder must be "indexed" to bring the different chasers to the hob. The indexing—that is the actual rotating of the die holder in the lead block is done by hand, the operator simply grasping the die and giving it a quarter turn. The latching means for holding the die holder during the operation of threading any particular chaser will now be described.

The die holder has four notches 45 in its periphery, these being located 90 degrees apart and adapted to receive the nose of a dog or latch 46. This latch is longitudinally slideable in a housing 47, and is operated by a hand lever 48 fulcrumed upon a pin 49 mounted in the block. These parts are shown in detail in Figs. 7, 9 and 10. This latch mechanism is adjustable along an arc concentric with the axis of the die holder, the result being that the clearance produced on the chaser may be regulated. In the present construction, a circular T slot 50 is formed in the upper surface of the lead block 5. This slot is enlarged at the point 51 for the insertion of the head 52 of bolts 53 which pass up through the housing 47. Consequently, the housing is circularly slideable but may be set at any desired point by screwing up the nuts 54 at the upper end of the bolts 53.

The boss 10 on the segment 11 is so formed that the axis of the hob is not precisely vertical but is inclined slightly (usually less than one degree) so that the path of the hob teeth while in contact with the chaser will conform to the pitch of the

thread desired. The lead block and die 65 holder rotate about non-coincident axes, the result being that a clearance is produced in the chaser.

In operation, the segment 11 of the hob carrier is first adjusted to the position required for the particular diameter of die to be manufactured. After this adjustment is once made the segment is not disturbed, ordinarily, until dies of a different diameter are wanted. The die holder latch 46 is then 75 adjusted in the slot 50 to such position as to produce the desired amount of clearance in the chaser. This adjustment will also remain undisturbed until dies of a different style or size are to be made. Next, the 80 blank die is fastened in the die holder by the aid of the set screws 33. The die holder is then rotated until one of the notches 45 therein comes opposite to the latch whereupon the latch is inserted and the die holder 85 is held fast. Next, the operator feeds the die to the hob by grasping the handle 6 and rotating the lead block 5, thereby bringing the end of the chaser gradually past the rotating hob and causing the latter to form 90 the teeth on the chaser. When this cutting operation is finished the operator indexes the holder—that is, he operates the lever 48 to withdraw the latch 46 and release the die holder. He then gives the die holder a 95 quarter turn and causes the latch to enter a fresh notch 45. At the same time he moves the handle 6 in the reverse direction to return it and the lead block to initial position. He thereupon proceeds to feed 100 the die forward again so as to bring the new chaser across the rotating hob to produce the teeth upon the chaser. This operation of indexing the die and then feeding it forward for the cutting operation is repeated 105 until the teeth are formed upon all four of the chasers.

It will be evident that our machine is simple in design, compact, and affords a wide range of adjustment. The segment 11, 110 contacting as it does, the table at three points, is very secure in its position and yet permits the hob to be readily adjusted for producing dies of different diameters. Again, it will be noted that the hob spindle and the boss wherein it is journaled occupy a position within the body, so to speak, of the die holder and lead block. The result is that the application of the force of the hob is close to the point where the driving power is applied to the spindle; in other words the spindle is short and is journaled in strong and substantial bearings. Another advantage in our construction results from the fact that the hob spindle and parts 115 which drive the same are beneath the surface of the table, thus affording a clear 120 space above the table and enabling the op-

erator to get close to his work without interference from upstanding obstructions.

What we claim as new and desire to secure by Letters Patent is:—

- 5 1. In a threading machine the combination of a stationary table, a rotatable die holder capable of receiving a die at its upper end, said die holder having a central opening, a hob, a hob spindle passing down through the central opening of the die holder, and means partially beneath the table and partially within the central opening of the die holder for supporting said spindle and driving it.
- 10 2. In a die threading machine the combination of a stationary table, a rotatable die holder having a central opening mounted on said table and adapted to hold a die at its upper end, a segment on the under side of said table pivotally connected thereto, means for adjustably securing said segment in different positions about its pivot, an upstanding boss rising from said segment and passing through the central opening of the die holder, a hob spindle journaled in said boss, and a hob at the upper end of said spindle.
- 15 3. In a die threading machine the combination of a stationary table, a die holder mounted thereon and rotatable about a vertical axis, said die holder being capable of supporting a die at the top and having a central opening, a hob, a hob spindle extending downward from the hob, a spindle support located partially within the central opening of the die holder and partially beneath the table, and means for adjusting said spindle support horizontally for producing dies of different diameters.
- 20 4. In a die threading machine the combination of a stationary table, a die holder mounted thereon and rotatable about a vertical axis, said die holder being capable of supporting a die at the top and having a central opening, a hob, a hob spindle extending downward from the hob, a spindle support located partially within the central opening of the die holder and partially beneath the table, said spindle support being horizontally adjustable, and means carried by said spindle support for driving said spindle in all positions of said spindle support.
- 25 5. In a die threading machine the combination of a stationary table, a lead block screwing into said table and having a vertical axis of rotation, a die holder laterally surrounded by said lead block, said die holder having a central opening, a spindle, and means at the lower end of said spindle for driving it, said driving means being beneath the table, and the spindle passing up through the central opening of the die holder.
- 30 6. In a die threading machine the combination of a stationary table, a lead block screwing into said table and having a vertical axis of rotation, a die holder screwing into said lead block and having a vertical axis of rotation, said die holder having a central opening and being adapted to carry a die at the top, a hob, a hob spindle extending down from said hob through the central opening of the die holder, and means within and beneath said die holder and table for supporting and driving said spindle.
- 35 7. In a die threading machine the combination of a stationary table, a lead block screwing thereto, a die holder screwing into the lead block, the lead block and die holder being rotatable about vertical axes, the upper surfaces of the table and lead block and die holder being approximately flush with each other, the die holder being annular, a post located within the die holder, a spindle journaled within said post, a hob at the upper end of said spindle, a segment supporting said post, said segment being pivoted to the bottom of the table, means for adjusting said segment about its pivot, and driving means for said post mounted on the under side of said segment.
- 40 8. In a die threading machine the combination of a stationary table, a rotatable lead block mounted on said table, a die holder rotatably mounted on the lead block, a hob, a hob spindle, a segment pivotally connected to the table and affording a bearing for the hob spindle, adjustable stops for arresting the segment at predetermined positions, and fastening means for fastening the segment into the position to which it has been adjusted.
- 45 9. In a die threading machine the combination of a stationary table, a lead block screwing into said table, a die holder rotatably mounted on said lead block and having an axis of rotation parallel to the axis of rotation of the lead block, and means for indexing the die holder with reference to the lead block, said indexing means being angularly adjustable.
- 50 10. In a die threading machine the combination of a stationary table, a lead block, a die holder rotatably mounted on the lead block, and an indexing latch on the lead block for holding the die holder fast during the act of cutting, said latch being adjustable on the lead block along an arc concentric with the axis of the die holder.
- 55 11. In a die threading machine the combination of a rotary hob having a stationary axis, a stationary table, a lead block screwing into said table, means whereby the lead block may be rotated, a die holder screwing into said lead block, said holder having a plurality of angularly distributed recesses

at its circumference, a sliding latch for entering said recesses for indexing the die holder, a housing in which said latch is slidable, circular ways concentric with the die holder and located on the lead block for guiding said housing, and means for fastening said housing at the desired point of said ways.

In witness whereof, we have hereunto subscribed our names in the presence of two ¹⁹ witnesses.
